UNITED STATES PATENT OFFICE.

HUGO LOEWENBACH, OF MILWAUKEE, WISCONSIN.

DESIGN FOR A MASK.

Application filed March 22, 1928. Serial No. 25,950. Term of patent 14 years.

To all whom it may concern:

Be it known that I, HUGO LOEWENBACH, a citizen of the United States, residing in Milwaukee, in the county of Milwaukee and State of Wisconsin, have invented a new, original, and ornamental Design for a Mask, of which the following is a specification, reference being had to the accompanying drawing, forming part thereof.

The mask has a cut out portion which is surrounded by surface ornamentation intended to represent a part of the face of an animal.

I claim:

The ornamental design for a mask, as shown, and described.

In testimony that I claim the foregoing I have hereunto set my hand at Milwaukee, in the county of Milwaukee, and State of Wisconsin.

HUGO LOEWENBACH.
